UNITED STATES PATENT OFFICE.

HAROLD F. SHAW, OF LEOMINSTER, MASSACHUSETTS, ASSIGNOR TO F. A. WHITNEY CARRIAGE COMPANY, OF LEOMINSTER, MASSACHUSETTS, A CORPORATION OF MASSACHUSETTS.

SEAT CONSTRUCTION FOR BABY CARRIAGES.

Application filed July 30, 1926. Serial No. 125,915.

This invention relates to a seat construction for baby carriages of the type having an adjustable back and the object is to provide an improved construction of this kind which will have various advantages as will appear as the following description of an illustrative embodiment of the invention proceeds. Such description may be read in connection with the accompanying drawings illustrating one form of the invention and in these drawings:

Fig. 1 is a central vertical section through a child's go-cart embodying an exemplary form of the invention in its construction;

Fig. 2 is a similar but fragmentary view on a larger scale showing the back in a different position of adjustment; and

Fig. 3 is a fragmentary section on the line 3—3 of Fig. 2.

Referring to the drawings, I have shown in Fig. 1 a vehicle of the go-cart type although my invention may be applied to other types of vehicle. I have therein shown a seat embodying a frame 5 supported from the running gear of the vehicle and a seat bottom 7 which in use will ordinarily be covered by a cushion, as indicated at 9 in dotted lines. Pivoted by hinges 11 at the rear of the seat is a back, the hinging being preferably so arranged that when the back is upright, as in the position of Fig. 1, the rear face of the back is substantially aligned with the rear edge of the seat, as shown in that figure. I have herein shown the back as embodying a suitable quadrilateral frame 13 and a back panel 15. The front face of this back will ordinarily be upholstered, as indicated at 17.

The back may be supported in various positions of angular adjustment, two of which are illustrated in Figs. 1 and 2 respectively, by means of a rod 19 carried thereby and adapted to be interlocked with a suitable retaining means carried by the seat. I prefer to pass the rod through the back to be enclosed thereby and herein have shown it as passing through the upper and lower members of the frame 13, the central portion of the rod being thus received between the side members of that frame, the two ends projecting at the top and bottom respectively. The upper end may be provided with a suitable handle 21 by means of which the rod may be manipulated. In the space defined by

the frame a suitable spring or similar mechanism may be housed which tends normally to move the rod 19 in one direction and I have herein (see Fig. 2) shown a helical spring 23 embracing the rod and interposed between the lower member of the frame 13 and a suitable washer 25 resting against a cotter pin 27 which passes through the rod. This spring normally tends to thrust the rod upwardly and may be depressed against the action of the spring by pressure on the handle 21.

When the locking rod is enclosed within the back in this manner the projecting lower end is brought to a position forward of the rear edge of the seat, the rear portion of the seat being suitably recessed as best seen at 29 in Fig. 3 to pass the same, and consequently for the purpose of holding the back in adjusted position the rod may be engaged with a suitable cooperating rack-like device disposed wholly forward of such rear edge. Herein the lower end of the rod is also bent forwardly or cranked to extend still further forward and in beneath the rear edge of the seat. To maintain the back the lower end of the rod is provided with suitable engaging means, herein typified by a short cross-head 31, the arms of which are adapted to rest respectively in the open bottom notches of a pair of notched plates 33 between which the rod works. The angular position of the back will obviously depend upon which one of the notches is engaged by the cross-head and herein provision is made for three positions, the two extreme positions being illustrated in Figs. 1 and 2 respectively. A mere lifting movement of the back from the position of Fig. 2 toward the vertical permits the cross-head 31 to pass from one position to the other moving over the projections between the notches in the manner of a ratchet on its return stroke, such projections being shaped somewhat similarly to ratchet teeth for this purpose. When it is desired to lower the back to the position shown in Fig. 2, the handle 21 is depressed, compressing spring 23 and releasing the cross-head from the notches and permitting the back to be swung rearwardly. The two notched plates 33 are preferably formed in one piece and I have herein shown them as connected by a web 35 which may rest, as shown, against the bottom 7 of the seat and they are also (see Fig. 3) provided with

outwardly turned flanges 37 by means of which they may be secured to the rear member of the seat frame 5 at either side of the recess 29 which is cut therein to pass the rod 19. 5 The web 35, as seen in Fig. 3, bridges over the recess 29 and thus serves to tie together the parts of the seat at opposite sides of such recess.

The construction shown is of a very neat 10 appearance. Furthermore, there are no objectionable projecting parts which are likely to catch the garments of the mother or nurse who is using the baby carriage. The catch means are disposed entirely out of the 15 way beneath the seat and may without objection be formed as shown with open topped notches forming toothlike projections. The greater portion of the rod and the spring which acts thereon are housed within the back 20 out of the way and no parts are exposed at the exterior of the carriage which are likely to become rusty or dirty and transfer such rust or dirt to the clothing.

Having described in detail the particular 25 embodiment of my invention shown in the accompanying drawings, which construction is merely illustrative since the principles of the invention may obviously be embodied in widely differing mechanical forms, what I 30 claim as new and desire to secure by Letters Patent I shall express in the following claims.

1. In combination with a seat a back pivoted thereto, the rear of said back adapted to 35 align with the back edge of the seat, a spring-pressed rod passing through the back forwardly of the rear face thereof, said seat being suitably recessed to pass the projecting

lower end of the rod, a cross-head on said lower end of the rod, and locking means for 40 the cross-head comprising a pair of notched plates between which the rod works secured at opposite sides of the recess and having a web connecting them across the recess.

2. In combination with a seat having at the 45 rear edge thereof a back hinged thereto, a spring-controlled rod mounted in and passing vertically through said back and having its upper end projecting therefrom at the top edge for manual reciprocation against said 50 spring substantially in the plane of said back, the lower end also projecting, and a rack-like structure on the bottom of the seat forwardly of the rear edge thereof to cooperate with said lower end whereby said back may be secured 55 in adjusted angular position relative to said seat.

3. In combination with a seat a back hinged thereto at the rear edge thereof comprising frame members and coverings for the 60 frame, a spring-controlled rod carried and supported by said frame members at the top and bottom of the back with the portion thereof which extends between said members received between said coverings and with its 65 ends projecting, the upper end providing a handle for operating the rod, and a rack-like structure on the bottom of the seat forwardly of the rear edge thereof with which the lower end of the rod cooperates whereby said back 70 may be secured in adjusted angular position relative to said seat.

In testimony whereof, I have signed my name to this specification.

HAROLD F. SHAW.
